SHAPER HOOD

Filed Sept. 19, 1927

Inventor:
Gerald Ty Hurlburt.

By Kent W. Womell Atty.

UNITED STATES PATENT OFFICE

GERALD TY HURLBURT, OF DETROIT, MICHIGAN, ASSIGNOR TO THE ALLINGTON & CURTIS MANUFACTURING COMPANY, OF SAGINAW, MICHIGAN, A CORPORATION OF MICHIGAN

SHAPER HOOD

Application filed September 19, 1927. Serial No. 220,453.

This invention relates in general to an improved dust collecting hood for shapers and similar machines and has more particular reference to a hood of this kind for preventing the accumulation and clogging of the hood by large pieces, splinters, knots and the like which are too heavy to be taken up by the vertical suction pipe.

An important object of the invention, therefore, is the provision of a shaper hood having a discharge opening for continuously getting rid of the heavier pieces by dropping them out of the hood by gravity upon the floor or into a suitable receptacle for periodical removal.

A further important object of the invention is the provision of an adjustable baffle plate to control the suction and therefore the upward tendency of the heavier particles so that too much of this material will not be in suspension in the vertical suction pipe for too long a time.

Other important objects will appear hereinafter, the drawings illustrating a preferred embodiment of the invention.

In the drawings—

Figure 1 is an elevation of a shaper hood constructed in accordance with the principles of this invention and located adjacent a rotating shaper head; and

Figure 2 is a plan view of the hood illustrating a shaper head for making a side cut upon a piece of timber.

In wood working factories equipped with exhaust fans and dust collecting systems of pipes, it is customary to employ such machines as shapers with rapidly rotating cutter heads for making side cuts on pieces of lumber and heretofore great difficulty has been experienced with hoods attached to the suction pipes for these machines on account of large pieces, splinters, knots, etc., from the lumber, in addition to the normal and finer shavings ordinarily made by the cutter head. The heavy pieces thrown by the knives into the hood are too heavy to be taken up by suction through the vertical suction pipe and consequently these parts accumulate in the back of the hood and gradually clog it up.

The present invention proposes to over-

come this objection by providing a discharge opening below the vertical section of the hood from which the larger pieces may be discharged by gravity. In accomplishing this result it is found desirable to provide a variable baffle plate which may be adjusted to control the suction, depending upon the size of the machines and the character of the cutting which is being done.

Referring more particularly to the drawings, the suction hood is located adjacent a cutter head 4 mounted upon a vertical spindle 5 in bearings 6 and rotated in any well known manner by a belt 7 and pulley 8. This cutter may be provided with adjustable blades 9 adapted to make a side cut, for example, upon a piece of lumber 10 which is moved progressively into cutting position.

The hood is ordinarily supported adjustably on a machine table adjacent the cutter head and is made of sheet metal with a somewhat irregular flaring receiver 11 having sides 12 and 13, varying in length, and top and bottom pieces 14 conforming thereto to provide an opening 15 which is inclined to the direction of feed of the lumber 10, the longer side 13 being disposed in the direction from which the lumber 10 is fed so that the particles which fly from the cutter head will be engaged thereby. The upper edge of the opening may be provided with a lip 16 for strengthening and protecting this portion of the hood and the interior surfaces of the receiver are provided with removable liners 17 which may be replaced as they become worn.

At the reduced end of the receiver 11 is a hood section 18 substantially rectangular in cross section to conform to the receiver 11 and having a suction head 19 at the top reduced to a circular extremity for receiving a suction pipe 20. At the bottom of the section 18 is an upwardly inclined shoulder 21 beyond which is an opening 22 below the suction head 19 or at the bottom of an inclined rear wall 23 which leads directly to the opening 22.

In the hood section 18 is a baffle plate 24 disposed directly above the inclined shoulder 21, which is movable at an angle into the section 18 to restrict or enlarge the opening between the shoulder 21 and the baffle plate,

thereby varying the suction for the receiving end of the hood. This baffle plate may be adjusted by bending it within the hood or it may even extend through a suitable slit at the upper edge of the section 18 and be variable from the outside of the hood.

In operation the velocity of the material thrown off by the cutter head will throw the material well up into the hood, and the suction will draw the lighter particles up through the suction pipe 20 in a well known manner. The baffle plate 24 is adjusted to control the suction for heavier particles so that they will not be held in suspension in the vertical portion of the hood but will drop by gravity through the opening 22 or against the inclined wall 23 and thence through the opening 22. The actual sizes and dimensions of these hoods depend upon the size of the machines for which they are used and the character of the work to be done, but it is found that hoods of this kind will save fully one half of the power otherwise required for keeping ordinary hoods and pipes clear.

It is obvious that various changes may be made in the construction, combination and arrangement of the parts without departing from the spirit and scope of this invention.

I claim:

- 30 1. In a suction hood for dust collecting systems, a converging reception portion opened at the end, a vertical suction discharge, a housing connecting the discharge and the reception portion comprising an opening below the suction discharge, and an inclined wall extending below the discharge and leading to the edge of the opening.
- 35 2. A suction hood for wood working machines having a flaring opening disposed adjacent the machine, a vertical suction pipe connection and a connecting portion between the suction pipe connection and the flaring opening, a baffle plate adjustable in the connecting portion to vary the suction as desired.
- 40 3. A suction hood for dust collecting, having a receiving opening at one end, a vertical suction pipe at the other end, an opening in the hood below the suction pipe opening, and an adjustable baffle plate in the hood above the said opening for varying the suction depending upon the character of material to be collected.
- 45 4. A suction hood for dust collecting systems, having a receiving opening at one end, a vertical suction pipe opening at the other end, an inclined wall below the suction pipe opening, a bottom opening at the lower end of the inclined wall, and a baffle plate within the hood above the said bottom opening to control the suction at the receiving end of the hood.
- 50 5. A collecting hood for saw dust or the like, having a receiving opening at one end, a suction opening at the other end, an inclined wall below the suction opening, a

shoulder in the bottom of the hood at a distance from the lower end of the inclined wall, a discharge opening between the shoulder and the lower end of the inclined wall, and a baffle plate in the hood above the said shoulder for controlling the suction at the receiving opening.

6. A suction hood for collecting saw dust and the like, comprising a rectangular open end portion and an opposite circular suction pipe outlet and an intermediate connecting portion; the connecting portion having an inclined wall below the suction opening with a discharge outlet at the bottom thereof, and a raised projection in the bottom wall at the other side of the opening; and a movable baffle plate in the connecting portion of the hood above the bottom projection and the discharge opening for controlling the suction at the open end.

7. In a suction hood for dust collecting systems, a suction pipe connection, an inclined wall below the pipe connection, and a discharge opening at the bottom of the inclined wall so that large heavy pieces drawn into the hood may be discharged by gravity therefrom, means forming a variable suction control above the discharge opening in the hood, and a rectangular flaring receiving portion having opposite sides one longer than the other, a strengthening lip overhanging the opening thereof, and metal liners for protecting the insides of the receiving portion.

8. A suction hood for collecting saw dust having an open end forming a receiver, a suction outlet at the top of the opposite end, and a discharge opening in the bottom, and a baffle plate bendable in the hood for varying the suction therein.
